ELECTRICAL CONNECTOR HAVING
RESILIENT INSERTWilliam A. Uline and Howard P. Howell, Sidney,
N. Y., assignors to Bendix Aviation Corporation,
New York, N. Y., a corporation of Delaware

Application February 11, 1946, Serial No. 646,788

12 Claims. (Cl. 173—328)

1

This invention relates to electrical connectors, and more particularly to connectors of the plug and jack or pin contact and socket contact type for connecting electrical conductors.

One of the objects of the present invention is to provide a pin and socket type connector having novel resilient means for mounting or supporting the pins and sockets thereof whereby said pins and sockets are unaffected by shock and vibration.

Another object of the invention is to provide a connector of the above character wherein the pins and sockets thereof, through provision of novel resilient mounting means therefor, are maintained free of all air, dirt, and moisture resulting in increased flashover and creepage distances.

Another object is to provide a connector of the above character having removable and interchangeable resilient mounting members of novel construction for the pins and sockets thereof.

A further object is to provide resilient inserts or mounting members and protective shells or retainers of novel construction for the contact pins and sockets of a connector whereby installation of said inserts or members in their respective retainers or shells is facilitated.

A still further object is to provide resilient pin and socket mounting members or inserts and protective shells or retainers novelly constructed so that location or orientation of said inserts and the pins and sockets carried thereby in definite positions within their respective shells or retainers is greatly facilitated to insure desired connections between and alignment of the various pins and sockets.

The above and further objects and novel features of the invention will more fully appear from the following detailed description when the same is read in connection with the accompanying drawings. It is to be understood, however, that the drawings are for the purpose of illustration only, and are not intended as a definition of the limits of the invention, reference for this latter purpose being had primarily to the appended claims.

In the drawings, wherein like reference characters refer to like parts throughout the several views,

Fig. 1 is a longitudinal section of the male assembly of a connector embodying the present invention;

Fig. 2 is a similar view, but of the female assembly of said connector embodying the present invention;

Fig. 3 is a horizontal section on the line 3—3 of Fig. 1; and

2

Fig. 4 is a horizontal section on the line 4—4 of Fig. 2.

Referring to the drawings, there is shown one form of a connector constructed in accordance with the present invention and comprising a detachable male assembly indicated generally at 5 (Fig. 1), and a cooperating fixed female assembly indicated generally at 6 (Fig. 2). As shown in Fig. 1, assembly 5 comprises a metallic, preferably aluminum, tubular shell 7 of novel construction which is formed with two axially spaced and communicating bores 8 and 9 of different diameters, the bore 8 being of a diameter less than the diameter of bore 9. Shell 7 is internally provided between the bores 8, 9 with an annular flange or projection 10 which is formed integrally with said shell and projects beyond the wall thereof surrounding bore 8, the latter terminating at said flange in a narrow, square annular shoulder or abutment 11, and the bore 9 terminating at said flange in a somewhat wider, but bevelled, annular shoulder or abutment 12. Shell 7 is provided in the wall thereof surrounding bore 8 with a longitudinal slot or keyway 13, and is further provided internally thereof with an inwardly projecting key 14 which extends through flange 10 and slightly beyond abutments 11 and 12 into the bores 8 and 9. Key 14 is formed integrally with shell 7 and is located in line with slot 13 in said shell. Shell 7 is externally threaded to receive a conductor and/or a conduit supporting adapter 15, and is externally provided with an annular flange 16 to receive a coupling nut 17 which is telescoped over said shell for coupling and electrically connecting the assemblies 5 and 6 together.

As shown, shell 7 of assembly 5 contains and protects the contact sockets which are resiliently and removably mounted within said shell by resilient mounting means of novel construction whereby said sockets will be unaffected by shock and vibration and will be maintained free of all air, dirt, and moisture, when assemblies 5 and 6 are coupled together, thus improving creepage and flashover conditions. As will appear hereafter, the novel construction of the socket mounting means in conjunction with the novel construction of shell 7 as hereinbefore described, simplifies installation and location or orientation of said mounting means and the sockets carried thereby within said shell. As shown, the socket mounting means comprises a round insert or member 18 of resilient insulating material, such as natural rubber or synthetic rubber, provided with a plurality of holes 19 to removably receive therein a corresponding plurality of contact sockets 20

and firmly hold the latter against longitudinal displacement from said insert under ordinary operating conditions. Each socket 20 is formed at one end with a pronged socket portion 21 disposed within the hole 19 to receive a contact pin hereinafter referred to, and at the opposite end which projects exteriorly of insert 18 with a solder well 22 to receive the conductor of an insulated lead 23.

Insert 18 is formed with an annular skirt portion 24 which is of a diameter slightly less than the diameter of the bore in flange 10, an enlarged annular portion 25 adapted to engage the wall of bore 8, and a still larger annular portion 26 axially spaced from the portion 25 and adapted to engage the wall of bore 9. Insert 18 is also formed externally thereof and between annular portions 25 and 26 with an annular groove or recess 27 adapted to receive the annular flange or projection 10 on shell 7, said recess having at one end a square annular abutment or shoulder 28 adapted to contact the abutment 11 on shell 7, and a bevelled annular abutment or shoulder 29 at the other end adapted to contact the shoulder 12 on said shell. The diameters of insert portions 25, 26 and of the portion containing the annular recess 27 are so proportioned that an interference fit of approximately .020 is provided whereby insert 18 will snugly fit within shell 7 and engage the respective surfaces thereof under compression.

Insert 18 is also provided in the periphery thereof with a keyway 30 adapted to receive the key 14 on shell 7, said keyway opening outwardly through the free end of insert portion 25 and extending through said portion and through recess 27 to a point slightly beyond the bevelled shoulder 29 on said insert. It will be noted that keyway 30 does not extend through the entire length of annular portion 26 of insert 18 so that the peripheral surface of said portion for a part thereof will remain continuous and will not be interrupted. Keyway 30 is located on insert 18 in a definite position with respect to the holes 19 in said insert and, as shown in Fig. 3, said keyway is located in diametrical alignment with two of said holes. If desired, more than one keyway 30 may be provided on insert 18, and the location of said keyways may vary depending upon the desired arrangement of contacts.

Insert 18 is inserted skirt end first into shell 7 through the bore 8 of the latter, and it will be noted that when the skirt portion 24 of the insert is introduced into bore 8 through bore 9 and the bore of flange 10, and the insert portion 25 is disposed within bore 9, the insert 18 will be free for rotation relative to shell 7 since the diameter of bore 9 is greater than the diameter of insert portion 25, and the diameter of the bore in flange 10 is slightly greater than the diameter of skirt portion 24. The insert 18 may then be easily rotated relative to shell 7, thus facilitating location or orientation of said insert with respect to said shell, and alignment of keyway 30 with key 14, whereby the contact sockets 20 will occupy definite predetermined angular positions in shell 7.

Upon location of insert 18 in proper position circumferentially of shell 7 determined by alignment of keyway 30 with key 14, pressure is then applied on the exposed end of the insert whereupon the portion 25 thereof is forced past the flange 10 facilitated by the bevelled abutment 12 on the shell 7, and the portion 26 of said insert is forced into bore 9 facilitated by the bevelled abutment 29 on the insert until the latter abutment contacts the bevelled abutment 12 on the

shell. At this time, the key 14 on shell 7 will be engaged in the keyway 30 on insert 18, the abutment 28 on the insert will contact the abutment 11 on the shell, the flange 10 on the shell will be engaged in the annular recess 27 on the insert, and the insert portions 25 and 26 will engage the walls of bores 8 and 9, respectively, under compression to provide a moisture and air tight seal. Insert 18 is now located in proper position within shell 7 and is retained in said shell against axial displacement in opposite directions by the cooperating abutments 11, 28 and 12, 29 and the annular projection 10. The contact sockets 20 may be inserted into insert 18 prior to or after mounting of said insert in shell 7. It will be noted that the cooperating key 14 and keyway 30 on the shell 7 and insert 18, respectively, in addition to serving as insert locating means, also prevents rotation of the insert 18 relative to shell 7 after said insert is completely mounted therein as hereinbefore described.

The leads 23 are supported in a grommet 31 of rubber or the like resilient insulating material which is loosely mounted within adapter 15 and is arranged to receive said leads and the exposed ends of the sockets 20, and to be seated in the ends of the holes 19 in insert 18 to make firm and sealing contact with the edges thereof when said adapter is threaded on the shell 7.

Referring now to Fig. 2, the assembly 6 comprises a metallic, preferably aluminum, tubular shell 32 of novel construction which is externally threaded to receive the nut 17 of assembly 5, and is externally provided with a flange 33 for bolting assembly 6 to a suitable support. Shell 32 is formed with a bore 34 to receive therein in telescoping relation the shell 7 of assembly 5, and disposed within said bore and formed integrally with shell 32 is a key 35 for cooperating with the slot 13 in shell 7 to align shells 7 and 32 and thereby insure desired connections between the sockets 20 in assembly 5 and the contact pins 36 in assembly 6.

Shell 32 is formed with axially spaced bores 37 and 38 of different diameters, the bore 37 being of a diameter less than the diameter of bore 38. For a purpose to appear hereafter, the diameters of bores 37 and 38 and the relative spacing thereof are the same as the spacing and diameters of the bores 8 and 9 in the shell 7 of assembly 5. Shell 32 is internally provided between bores 37 and 38 with an annular flange or projection 39 which is formed integrally with said shell and projects beyond the wall thereof surrounding bore 37, the latter terminating at said flange in a narrow, square annular shoulder or abutment 40, and the bore 38 terminating at said flange in a somewhat wider, but bevelled, annular shoulder or abutment 41. Flange 39 and abutments 40, 41 are also of the same size and conformation as the flange 10 and abutments 11 and 12 in shell 7 of assembly 5. Shell 32 is further provided internally thereof with a short key 42 which extends the length of bore 37, through flange 39 and slightly beyond abutment 41, and is of the same dimensions as the dimensions of key 14 in shell 7 of assembly 5. Key 42 is formed integrally with shell 32 and is located in line with key 35 so as to occupy the same relative position in said shell 7 as the key 14 in shell 7.

The contact pins 36 are removably mounted within shell 32 by resilient mounting means of novel construction, whereby said pins will be unaffected by shock and vibration and will be maintained free of all air, dirt, and moisture when

coupled with assembly 5. The novel construction of said mounting means in conjunction with the novel construction of shell 32 also simplifies installation and location or orientation of the mounting means and the pins 36 carried thereby within said shell so that said pins will be located in shell 32 with respect to key 35 the same as the sockets 20 are located in shell 7 with respect to slot 13. As shown, the contact pin mounting means comprises a round insert or member 43 of resilient insulating material, such as natural rubber or synthetic rubber, provided with a plurality of holes 44 to removably receive therein the pins 36 and firmly hold the latter against longitudinal displacement relative to said insert under normal operating conditions. Holes 44 correspond in size and conformation with the holes 19 in insert 18 so that the sockets 20 and pins 36 are interchangeable in their inserts 18 and 43. Pins 36 project beyond one end of insert 43 into bore 34 to receive the sockets 20, and beyond the opposite end of said insert and have electrically connecting therewith, as by soldering, the conductors of insulated leads 45.

Insert 43 is formed with an annular portion 46 adapted to engage the wall of bore 37, and an enlarged annular portion 47 axially spaced from the portion 46 and adapted to engage the wall of bore 38, said portions being identical with the portions 25 and 26, respectively, of insert 18 in diameter, length, and spacing. Insert 43 is provided in the periphery thereof and between the portions 46, 47 with an annular groove or recess 48 adapted to receive therein the annular flange or projection 39 on shell 32, said recess having at one end a square annular shoulder or abutment 49 adapted to contact the abutment 40 on shell 32, and a bevelled annular abutment or shoulder 50 at the other end adapted to contact the abutment 41 on said shell. The recess 48 and the abutments 49 and 50 on insert 43 are identical with the recess 27 and abutments 28 and 29 on insert 18 in size and conformation. Insert 43 is also provided in the periphery thereof with a keyway 51 adapted to receive the key 42 on shell 32, said keyway opening outwardly through the free end of insert portion 46 and extending through said portion and through recess 48 to a point slightly beyond the bevelled abutment 50 on said insert. Keyway 51 is the same in size as the keyway 30 in insert 18, and is located on insert 43 with respect to the holes 44 therein in the same position as keyway 30 is located on insert 18 with respect to the holes 19 therein.

Insert 43 is inserted into shell 32 through the bore 38 and in effecting this operation, the annular portion 46 of said insert is first introduced into the bore 38 and since the latter is greater in diameter than the diameter of said portion, the insert may be easily rotated relative to shell 32 to locate the same in proper position circumferentially of said shell, determined by aligning keyway 51 with key 42. Pressure is then applied on the exposed end of the insert 43 whereupon the portion 46 thereof is forced past the flange 39 facilitated by the bevelled abutment 41 on the shell, and the portion 47 is forced into bore 38 facilitated by the bevelled abutment 50 on the insert until the latter abutment contacts the bevelled abutment 41 on the shell. At this time, key 42 will be engaged in keyway 51, abutment 49 will contact abutment 40, flange 39 will be engaged in recess 48, and the portions 46 and 47 of the insert will engage the walls of bores 37 and 38, respectively, under compression to provide a moisture and air tight seal.

In effecting connection between the sockets 20 and pins 36, the keyway 13 is aligned and engaged with key 35 before sockets 20 and pins 36 are engaged, and the shells 7 and 32 are then telescoped, whereupon the sockets 20 and pins 36 are also telescoped and the connection made substantially permanent by rotating the clamping nut 17 until adjacent ends of the inserts 18 and 43 firmly abut each other.

It will thus be noted that by means of the keys 14 and 42 and keyways 30 and 51 accurate angular location or orientation of the inserts 18 and 43 with respect to the slot 13 and key 35 is facilitated and assured, whereby the sockets 20 and pins 36 will be accurately aligned and only the desired connections between said pins and sockets will be effected when the shells 7 and 32 are telescoped. It will further be noted that since the inserts 18 and 43, except for the skirt portion 24 on insert 18, are otherwise identical in size and conformation, said inserts are interchangeable in shells 7 and 32.

There is thus provided a connector of the pin and socket type wherein the contact sockets and pins thereof are mounted in cooperating protective shells and resilient inserts of novel construction, whereby said sockets and pins will be unaffected by vibration and shock, will be maintained free of all dirt, air, and moisture, and angular location or orientation of said inserts with respect to said shells in a predetermined relation is facilitated.

Although only a single embodiment of the present invention has been illustrated in the accompanying drawings and described in the foregoing specification, it is to be expressly understood that the invention is not limited to said embodiment. Various changes may be made therein, particularly in the design and arrangement of the parts illustrated, and in the materials used, without departing from the spirit and scope of the invention, as will now be apparent to those skilled in the art. For a definition of the limits of the invention, reference is had primarily to the appended claims.

What is claimed is:

1. In an electrical connector of the pin contact and socket contact type, a rigid shell having two axially spaced bores of different diameters and an internal annular flange between said bores, the larger diameter bore terminating at said flange in a bevelled annular abutment 55 and the smaller diameter bore terminating at said flange in a square annular abutment, a resilient member disposed within said shell and adapted to receive a plurality of said contacts, said member having axially spaced annular portions of different diameters engaged with the walls of said bores and an annular recess between said portions into which said flange projects, said recess having at one end thereof a bevelled annular abutment in contact with the bevelled abutment on said shell and at the opposite end a square annular abutment in contact with the square abutment on said shell, and cooperating means comprising a key on said shell and a keyway on said member for locating the latter in a predetermined angular position with respect to said shell, said key and keyway extending across said flange and traversing no more than a portion of the larger diameter bore engaged by said resilient member.
2. In an electrical connector of the pin con-

tact and socket contact type, two rigid telescoping shells, each of said shells having two axially spaced bores of different diameters and an internal annular flange between said bores, the larger diameter bore terminating at said flange in a bevelled annular abutment and the smaller diameter bore terminating at said flange in a square annular abutment, a resilient insert mounted within one of said shells with a plurality of socket contacts, a resilient insert mounted within the other of said shells with a corresponding plurality of pin contacts, said inserts having annular portions contacting the walls of the bores, the flange, and the abutments in their respective shells, cooperating means on said shells and said inserts for locating the latter in predetermined angular positions in said shells, said cooperating means terminating short of the outer end of the annular portion of the insert in engagement with said larger diameter bore, and cooperating means on said shells for coupling the same and said socket and pin contacts in telescoped relation, said contacts being mounted in axially extending passages through said inserts and removably held therein by internal flanges in said passages engaging annular grooves intermediate the ends of said contacts.

3. In an electrical connector of the pin contact and socket contact type, a one-piece rigid tubular shell having two axially spaced bores of different diameters and an internal annular flange between said bores constituting the most constricted portion of the passage through the shell, the larger diameter bore terminating at said flange in a bevelled annular abutment and the smaller diameter bore terminating at said flange in a square annular abutment, a resilient member disposed within said shell and adapted to receive one of said contacts, said member having axially spaced annular portions of different diameters engaged with the walls of said bores under radial compression in at least the larger diameter bore and an annular recess between said portions into which said flange projects, said recess having at one end thereof a bevelled annular abutment in contact with the bevelled abutment on said shell and at the opposite end a square annular abutment in contact with the square abutment on said shell, whereby said member is insertable axially into the shell from the bevelled side of said flange and removable therefrom in the same direction without damage to said member.

4. In an electrical connector of the pin contact and socket contact type, two rigid telescoping shells, each of said shells having two axially spaced bores of different diameters and an internal annular flange between said bores, the larger diameter bore terminating at said flange in a bevelled annular abutment and the smaller diameter bore terminating at said flange in a square annular abutment, said square annular abutments being in spaced face-to-face relation, a resilient insert mounted within one of said shells adapted to receive a plurality of said socket contacts, a resilient insert mounted within the other of said shells adapted to receive a plurality of said pin contacts, said inserts having annular portions contacting the walls of the bores, the flange, and the abutments in their respective shells, and cooperating aligning means on said shells and on each shell and its insert for coupling the shells and said socket and pin contacts in aligned relation, and means for axially compressing said inserts in end to end en-

gagement between said square annular abutments.

5. In an electrical connector of the pin contact and socket contact type having laterally disposed space providing for the flow of a resilient insert member under compression, a one-piece rigid tubular shell, a resilient member removably disposed within said shell, at least a portion of said member being under radial compression and having an uninterrupted cylindrical periphery in engagement with a smooth cylindrical portion of said shell, means including an axially extending key in the shell and a co-operating groove in said member for angularly orienting the member in the shell, said key terminating short of the end of the shell which is sealed there beyond by the compressed material of the insert member, a plurality of contacts mounted in the insert member in positions oriented with respect to said key, and means including an annular recess in said member and an internal annular projection on said shell engaged in said recess for retaining said member in said shell, said recess and projection having at corresponding ends thereof cooperating bevelled and square annular abutments, the diameter of the insert and shell at the bevelled abutment being greater than at the square abutment.

6. In an electrical connector, a rigid tubular shell having two axially spaced bores of different diameters and an internal annular flange between said bores, said flange being of smaller inside diameter than the smaller diameter bore and having a bevelled shoulder on the side of the larger diameter bore, and a resilient contact supporting insert in said shell having axially spaced annular portions of different diameters for engagement with said bores, and an annular groove shaped to engage said flange, said annular portion of larger diameter being under radial compression in said larger diameter bore.

7. An electrical connector as defined in claim 6 including an axially extending, radially projecting key in said shell extending across only a portion of said larger diameter bore, and a keyway for said key in the insert terminating short of the end of the larger diameter portion of said insert which is remote from said groove.

8. In an electrical connector, a rigid shell having at least two axially spaced bores of different diameters and an internal annular flange connecting said bores, the larger diameter bore terminating at said flange in a bevelled annular abutment and the smaller diameter bore terminating at said flange in a substantially radial annular abutment, a resilient contact supporting insert in said shell having axially spaced annular portions of different diameters for engagement with the walls of said bores and an annular groove connecting said portions, said groove being shaped to engage the contours of said flange, and said larger diameter portion of said insert being under radial compression in said larger diameter bore, an axially extending key in said shell extending across only a portion of said larger diameter bore and being approximately flush with the inner diameter of said flange, and a keyway in said insert for said key terminating short of the end of the larger diameter portion of said insert which is remote from said groove.

9. In an electrical connector, a rigid tubular shell having at least two axially spaced bores of different diameters and an internal annular flange connecting said bores, the inner end of

the larger diameter bore terminating at said flange in a bevelled annular abutment and the inner end of the smaller diameter bore terminating at said flange in a substantially square annular abutment, a resilient contact supporting insert in said shell having a plurality of passages for contacts and axially spaced annular portions of different diameters engaging the walls of said bores under radial compression and an annular groove connecting said portions, said groove being shaped to receive and closely engage the walls of said flange, an axially extending key in said shell extending across said flange with the end thereof adjacent said larger diameter bore terminating short of the outer end of said larger diameter bore, said insert having a keyway in said annular portions thereof for receiving said key and said keyway terminating short of the end of said annular portion which engages the wall of the larger diameter bore in the shell, whereby at least part of said insert has compressive engagement with said larger diameter bore entirely around the periphery thereof.

10. An electrical connector as defined in claim 9 wherein said insert has an end portion within the small diameter bore of the shell having a diameter slightly less than the inner diameter of the flange in the shell.

11. An electrical connector as defined in claim 9 wherein said insert has at least one axially extending passage therethrough, the central portion of each said passage having a reduced diameter to form an internal flange within the flange in the shell, and a contact member mounted in each said passage and having a reduced central portion forming an annular groove thereon engaged by said flange in the passage

to yieldably hold the contact member against axial displacement.

12. The combination comprising two electrical connector assemblies as defined in claim 11 wherein the insert in one assembly supports socket contact members and the insert in the other assembly supports pin contact members, and means for detachably securing said assemblies together with said pin and socket contact members in telescoping engagement, the shells thereof in telescoping relation and the adjacent ends of the inserts in end-to-end engagement under compression, whereby each insert is pressed axially against the square annular abutment of the flange in the mounting shell therefor.
